UNITED STATES PATENT OFFICE.

ARTHUR T. DAWSON AND GEORGE T. BUCKHAM, OF LONDON, ENGLAND,
ASSIGNORS TO THE VICKERS, SONS & MAXIM, LIMITED, OF SHEFFIELD,
ENGLAND.

EXTRACTING MECHANISM FOR BREECH-LOADING GUNS.

SPECIFICATION forming part of Letters Patent No. 680,192, dated August 1, 1899.

Original application filed May 16, 1898, Serial No. 680,834. Divided and this application filed February 1, 1899. Serial No. 704,117. (No model.)

To all whom it may concern:

Be it known that we, ARTHUR TREVOR DAWSON and GEORGE THOMAS BUCKHAM, citizens of England, residing at No. 28 Victoria street, 5 Westminster, London, England, have invented certain new and useful Improvements in Extracting Mechanism for Breech-Loading Guns, (for which we have applied for patents in Austria, dated September 9, 1898, No. 14,752; 10 in Denmark, dated September 6, 1898; in France, dated September 6, 1898, No. 268,988; in Germany, dated September 5, 1898; in Great Britain, dated October 20, 1897, No. 24,264; in Italy, dated September 6, 1898, No. 14,752; 15 in Norway, dated September 6, 1898, No. 10,226; in Spain, dated September 6, 1898, and in Sweden, dated September 6, 1898,) of which the following is a specification, being a division of our application for Letters Patent filed May 16, 1898, Serial No. 680,834.

Our invention relates to improvements in extracting mechanism for breech-loading guns, as we shall describe, referring to the accompanying drawings.

Figure 1 is a transverse section of the breech of a gun with cartridge-extractor in elevation. Figs. 2 and 3 are plans, partly in section, showing the breech closed and opened, respectively; and Figs. 4 and 5 are corresponding views, 30 drawn to an enlarged scale, of part of the extractor and the hammer.

These improvements were originally included in our application filed May 16, 1898, Serial No. 680,834, but have been made the 35 subject of a new application, a division having been required by the examiner.

In a lateral hole in the breech of the gun we fit an extractor-rod e , having its end sloped off, so as to engage in front of the flange f of 40 the cartridge-case F . The rod e is prevented from turning by a projecting stud e' , engaged

in a lateral groove, and the outer end of the rod is made with a slot e^2 on its rear side and a projection e^3 on its under side. On the boss of the breech-plug carrier C are fixed a hammer-arm h and two projecting parts h' and h^2 , h^2 being in the plane of the slot e^2 and h' in the plane of e^3 . When the cartridge F is in place and the breech is closed, the rod e is in the position shown in Figs. 1, 2, and 4. On throwing back the carrier C , as shown in Fig. 3, the hammer-arm h strikes the head of the rod e , pushing it inward, so that its sloping part, acting on the flange f , starts the extracting movement of the cartridge-case. On again closing the breech the projection h' , acting on the projection e^3 , causes the rod e to move back to the position shown in Figs. 1, 2, and 4.

The projecting part h^2 , engaging the groove e^2 , prevents the rod from being moved accidentally out of position when the breech is closed.

Having thus described the nature of this invention and the best means we know of carrying the same into practical effect, we claim—

In a breech-loading gun, the combination of the breech-plug carrier having a hammer-arm h and two projections h' and h^2 , and a sliding rod e having at its outer end a slot and projection engaged by the projections on said carrier and having its inner end sloped to engage in front of a cartridge-flange, substantially as described.

In testimony whereof we have hereunto set our hands in presence of two subscribing witnesses.

A. T. DAWSON.
G. T. BUCKHAM.
